UNITED STATES PATENT OFFICE.

PETER KUCERA, OF SOUTH CONNELLSVILLE, PENNSYLVANIA, ASSIGNOR TO CAPSTAN GLASS COMPANY, OF CONNELLSVILLE, PENNSYLVANIA, A CORPORATION OF DELAWARE.

METHOD OF MANUFACTURING RING MOLDS AND THE LIKE.

Original application filed January 6, 1920, Serial No. 349,704. Divided and this application filed July 9, 1921. Serial No. 483,422.

To all whom it may concern:

Be it known that I, PETER KUCERA, a citizen of the United States, residing at South Connellsburg, in the county of Fayette, State of Pennsylvania, have invented certain new and useful Improvements in Methods of Manufacturing Ring Molds and the like, of which the following is a specification.

10 The present invention relates broadly to metal working, and more particularly to a method for manufacture and repair of ring molds adapted for use in pressing glassware and the like.

15 The principal object of the present invention is a method comprising displacing metal from the body of the ring mold to form a hard, compact edge, then shaping the displaced metal to bring the mold to 20 the required size.

Another object of the present invention comprises the method of treating worn ring molds by applying pressure to the mold to 25 re-shape the matrix portion of the mold and to displace a side wall of the mold whereby sufficient metal is provided to permit re-forming of the mold to the required size.

30 A further object of the present invention is the method of treating worn glass-pressing mold parts by expanding the metal at the worn portion of the part, then re-shaping the part to the desired shape and dimension.

35 A further and more specific object of the present invention is the method of treating worn portions of glass-pressing devices by expanding the metal adjacent the worn part to a position beyond the dimension 40 required, then cutting away the excess metal to obtain the desired dimension.

45 A further and more specific object of the present invention is the method of repairing worn ring molds by displacing the metal radially and inwardly on the inner side of the ring to lessen the internal diameter of the ring, then re-shaping the inner diameter of the ring to the required shape and size.

50 A still further and more specific object of the present invention is the treatment of

worn ring molds which comprises spinning the inner edge of the ring mold inwardly to contract the opening in the ring to a diameter less than the required size, then cutting away the metal until the desired diameter is obtained. 55

Other and further objects of the present invention will in part be obvious and will in part be pointed out hereinafter by reference to the accompanying drawings forming a part of the present application and wherein like parts are designated by like characters throughout the several figures thereof. 60

Realizing that the present invention may be carried out by methods other than those herein disclosed I desire that the disclosure herewith shall be considered as illustrative and not in the limiting sense. 65

70 Figure 1 illustrates a block mold with an improved ring mold made in accordance with the present invention and a plunger forming a glass tumbler.

75 Figure 2 is an enlarged view of a section of the ring mold shown in Figure 1.

Figure 3 illustrates the condition of a worn ring mold with the normal shape shown in dotted lines.

80 Figure 4 illustrates a worn ring mold after a spinning operation has been performed thereon.

85 Figure 5 illustrates a mold shown in Figure 4 after the front edge thereof has been recut by reaming or boring.

Figure 6 illustrates a spinning mechanism at the beginning of the operation to restore a worn ring; and

90 Figure 7 shows a front view of one form of spinning tool.

95 In the manufacture of all pressed glassware a plastic charge of hot glass is dropped into a block mold which is usually in the form of a cup with the interior diameter corresponding in shape to the article to be made. A plunger is adapted to shape the interior of the article and to force the plastic glass into contact with the walls of the block mold. The upper edge of the article is usually finished by a separate mold part 100 known as a ring mold which is tightly held in position on the block mold when the

plunger is driven therein to shape the glass. The shaping operation usually is performed under great pressure and the glass in attempting to escape tends to flow between the plunger and the ring mold. This subjects the inner edge of the ring mold to great heat and excessive pressure so that this edge tends to wear away quickly. When the edge is worn "fins" or "burs" appear on the upper edge of the tumblers being made. Obviously as soon as these fins or burs occur in any size the ware is rejected and the ring mold must be replaced. Heretofore it has been customary to throw rings away or if the factory were making different sized tumblers the ring mold might be recut for a larger size. Where a factory is making but one size this cannot be done. Consequently the rings when worn are usually discarded thereby adding greatly to the cost of the finished ware.

The present invention overcomes the difficulties of the known art by displacing the metal adjacent the inner wall of the ring inwardly whereby the opening in the ring is contracted. This displacement may be accomplished in different ways, but the preferred way is that of spinning. By the spinning method the ring is mounted in a suitable chuck and is subjected to a spinning roll moved under pressure in the direction of the axis of the ring, so that the desired displacement of the metal is accomplished. After an excess of metal has been displaced, the required diameter may be obtained by spinning the metal back to the exact diameter desired, or a very slight cut may be made with a suitable lathe tool or otherwise, (for example by means of a reamer), and the ring is again ready for use.

The invention also contemplates the manufacture of ring molds by this method in view of the fact that the metal adjacent the edge of the mold is compressed and consequently is harder than the adjacent metal, thereby being of greater wearing qualities and being better able to withstand the higher temperature due to the hot plastic glass. The present invention, therefore, comprises both an article of manufacture and a method for producing the same.

Referring more particularly to the drawings and to the Figures 1 and 2, the block mold 1 is provided at its upper edge with a recess in which the ring mold 2 is adapted to set. When the plunger 4 enters the block mold 1 having a suitable charge of glass therein, the glass article, which may comprise a tumbler 5, is pressed between the block mold, the ring mold, and the plunger. It is obvious that the glass is displaced upwardly around the plunger 4 as the plunger descends into the mold and that in view of the plastic condition of the melted glass it attempts to escape between the plunger and the ring

mold. This tendency places extra heavy duty upon the small corner or edge 3 of the ring mold.

Referring more specially to Figure 2, which illustrates a section of the ring mold in accordance with the present invention, it is to be noted that the edge 3 adjacent the recess 6 is illustrated as being formed of hardened or compacted metal. This greatly assists in the prolongation of the life of this edge.

Referring now to Figure 3, which illustrates an exceedingly worn ring mold, and in this illustration it is to be noted that the surface 7, which is adjacent the plunger, has become worn away to the position of 7^a and that the edge is worn away and assumes the position as shown at 8, whereas the normal edge is shown in dotted lines as at 3.

The worn ring 2 is adapted to be mounted in a chuck 9, (Fig. 6), and is subjected to the action of the spinning tool which comprises a body 10 that carries a spinning head 11 upon a suitable post 12. This spinning tool is mounted on a suitable machine tool, (not shown), and is urged under pressure in the direction of the arrow A. This compresses and displaces the metal adjacent the recess 6 in such manner that the metal is displaced inwardly and assumes the position 7^b, as illustrated in Figure 4, and wherein the normal position desired is indicated in dotted lines as at 7. The spinning tool is then removed and the excess of metal as at 7^b is removed either by cutting away the metal with a suitable lathe tool, or by any other well known metal shaping operation, until the inner surface has assumed the cylindrical form desired and indicated by the position 7. The worn ring is again ready for use and is equally as good as a new ring.

It is to be understood that the present method is also applicable to the manufacture of rings in the first instance, and that it produces a ring wherein the metal in the edge 3 is compacted upon itself, as is illustrated in Figures 2, 4, and 5, so that the edge is better enabled to withstand the heavy duty that is imposed upon this small portion of metal.

This application is a division of my prior application filed January 6th, 1920, Serial Number 349,704.

Having thus described my invention, what I claim is:

1. The method of manufacturing molds for pressed glassware which comprises producing a matrix of approximately the desired shape, then subjecting portions of the mold to compression forces to compact and harden the said portions, then finishing the hardened portions to the desired size and shape.

2. The method of manufacturing ring molds for pressed glassware which comprises producing a ring matrix of approximately

the shape desired, then subjecting edge portions of the ring mold to compression forces to compact and harden the said edge portions, then finishing the hardened portions 5 to the desired size and shape.

3. The method of manufacturing molds for pressed glassware and the like which molds have projections adapted to sustain pressure and adapted to shape a part of the 10 finished article, which method comprises subjecting the metal at and adjacent to the projections to forces to compact and to harden the metal in the said projections, and then shaping the compacting metal.

15 4. The method of manufacturing ring molds for pressed glassware and the like which method comprises subjecting the inner edge of the ring mold to compression forces to compact and harden the said edge, and 20 then finishing the edge to the desired dimension and form.

5. The method of manufacturing ring molds for pressed glassware and the like which method comprises displacing metal 25 from the matrix portion toward the inner edge of the ring mold to provide an excess of metal at the said edge, and then cutting away the excess of metal at the edge to obtain the desired dimension and form.

30 6. The method of manufacturing ring molds for pressed glassware and the like which method comprises forming the ring

mold to substantially the shape and dimension desired then spinning the metal adjacent the inner edge of the ring radially inwardly, and then finishing said edge to the 35 desired shape and dimension.

7. The method of manufacturing ring molds for pressed glassware and the like which method comprises forming the ring 40 mold to substantially the shape and dimension desired, then spinning the metal from the bottom of the matrix groove adjacent the inner edge of the ring radially inwardly, and then finishing said edge to the desired 45 shape and dimension.

8. The method of repairing worn ring molds which method comprises displacing metal from the body portion of the ring toward the inner edge and in excess of the 50 amount of metal required for an inner edge, then refinishing an inner edge of the desired shape and dimension from the said excess of displaced metal.

9. The method of repairing worn ring molds which method comprises renewing the matrix groove by displacing metal from the body portion of the ring toward the inner edge and in excess of the amount of metal required for an inner edge, and refinishing the inner edge to provide the desired 55 shape and dimension from said excess of displaced metal.

PETER KUCERA.
